UNITED STATES PATENT OFFICE.

VINTON U. D. PIERCE, OF WASHINGTON, DISTRICT OF COLUMBIA; JOSIAH PIERCE
EXECUTOR OF SAID V. U. D. PIERCE, DECEASED.

SUPERCHARGER FOR AEROPLANE ENGINES.

Application filed June 25, 1921. Serial No. 480,440.

This invention relates to means whereby the engine of an aeroplane can be forced to operate under sea level conditions and therefore deliver normal horsepower irrespective of the altitude at which the engine happens to be, and particularly to those superchargers in which reciprocating piston pumps are used for delivering into each cylinder a greater weight of air than ordinarily would be drawn in as the piston of the engine moves downward on its suction stroke.

As is well known, the air becomes thinner the higher the altitude, and as a consequence an engine which has a certain power at sea level has its power decreased as its altitude increases. To avoid this many different forms of superchargers have been devised operating to force the charge into the cylinder of the engine upon the suction stroke so as to compensate for decreased air pressure.

One of the main difficulties incident to supercharging is to provide means whereby the supercharging can be easily and delicately regulated to compensate for differences in air pressure at various altitudes, and it is common practice to hold the supercharger mechanism out of operation until the engine has reached a certain altitude, as for instance ten or fifteen thousand feet, and then the supercharger is put in operation and delivers its maximum charge.

The general object of this present invention is to provide a supercharger for the purpose described which delivers air through the carburetor of the engine, the carburetor being provided with its own air intake for use at sea level or low altitudes, and provide means whereby the air delivered from the supercharger may either be all directed through the carburetor and so into the cylinders of the engine, or whereby a portion of the air passing from the supercharger may pass to the engine and a portion of the air be relieved.

A further object is to provide a valve for the purpose of controlling the passage of air to the engine which shall be of very simple yet effective construction and which may be easily regulated to secure any desired pressure of air within the cylinders within range of the mechanism.

A further object is to provide a construction of such simplicity that it may be dis-

posed between the engine bank and the propeller of the engine and which includes reciprocating pumps having the cylinders of such proportions and pistons operating at such speeds that one cylinder of the pump will take care of and furnish air for a plurality of engine cylinders.

Another object is to provide a construction of this kind wherein the pump cylinder has a capacity twice that of any engine cylinder and so geared to the crank shaft of the engine that the piston of the pump will reciprocate twice as fast as the pistons of the engine, thus permitting one cylinder of the pump to deliver air sufficient for a plurality of cylinders.

Still another object is to provide a maximum inlet for the air to the pumping cylinder and a maximum outlet for the air to the cylinders of the engine.

Other objects will appear in the course of the following description.

My invention is illustrated in the accompanying drawings, wherein:—

Figure 1 is a front elevation of an aeroplane engine provided with my improved supercharger;

Figure 2 is a side elevation of the engine with a portion of the propeller of the aeroplane, the crank case of the supercharger being broken away;

Figure 3 is a fragmentary sectional view through the upper end of one of the pumping cylinders showing the inlet and outlet valves thereof, the outlet pipe leading from the pumping cylinder being also broken away to show the interior of the relief valve casing;

Figure 4 is an enlarged top plan view of the inlet and outlet valve casings of the pump showing the manner in which the valves are operated by the cam shaft of the engine;

Figure 5 is an outside face view of the valve 35 and the frame supporting the valve;

Figure 6 is an end elevation of an aeroplane engine with a single pumping cylinder applied thereto;

Figure 7 is a longitudinal sectional view through the pumping cylinder showing the valves, the engine being shown in elevation;

Figure 8 is a top plan view of the pumping cylinder and its allied parts;

Figure 9 is a horizontal sectional view through the crank case of the pumping cyl-

inder showing the lower set of inlet and exhaust valves, the section being taken on the line 9—9 of Figure 7 looking in the direction of the arrows.

5 In the drawings, I have illustrated a Hispano-suiza aeroplane engine and have illustrated my invention as applied thereto, but this is purely for illustrative purposes, and it will be understood that the invention may 10 be equally well applied to any other make of engine and that I do not wish to be limited to the use of my invention applied to a V-type engine.

In these drawings, A designates the crank 15 case of the engine, B the engine block, C the intake manifold, and D the carbureter which has an air inlet opening at any desired point, as for instance at the end d, and which is used under ordinary circumstances. 20 Extending through the crank case is the usual crank shaft E which is connected to the propeller F. All of these parts are of any suitable or usual construction.

Mounted upon the engine block or crank 25 case between the engine block and the propeller are two outwardly divergent pumping cylinders 10. These are illustrated in Figure 1 as single acting pumping cylinders, and operating within each cylinder 10 is 30 the usual trunk piston 11. These pistons are connected to the downwardly converging piston rods 12, which in turn are connected to a crank 13 disposed in the housing 14 which is common to both of the cylinders 35 10, this crank being operatively connected to a crank shaft 15 illustrated as carrying upon it a sprocket wheel 16 driven by a sprocket chain 17 from a sprocket wheel 18 mounted upon the crank shaft E of the motor. These 40 sprocket wheels 16 and 18 and the sprocket chains 17 are contained within a housing 19. Any other suitable gearing may be used, however. It will be noted that the proportions of the sprocket gears and gear wheels 45 16 and 18 are such that the shaft 15 is driven at twice the speed of the shaft E.

The housing 14 as illustrated rests upon and is bolted to the extremity of the crank case A, and the housing is triangular in side 50 elevation so as to provide two faces extending in an upwardly convergent relation, these faces supporting and being bolted to the flanged ends of the cylinders 10. The outer ends of the cylinders 10 are formed 55 with relatively elongated intake ports 20 which open into the chamber 21 which extends transversely across the upper end of the cylinder 10, as illustrated in Figure 3, this chamber having an intake valve seat 60 22 and an outlet valve seat 22^a, the middle portion of the chamber being formed to provide guides for the stems of valves 23 and 24. Preferably there are two intake valves 23 and two outlet valves 24, these valves being 65 held to their seats by springs 25 and

being positively opened by cams on cam shafts 27 driven from the main cam shaft 26 of the engine. Where four valves are used, two intake valves and two outlet valves as illustrated, the cam shaft 26 of the engine is provided with a gear wheel 26^a which meshes with pinions 27^a mounted on cam shafts 27, there being a cam shaft 27 for each pair of inlet and outlet valves. These cam shafts 27 carry on them the double 70 cams 28 and 29 so formed that one rotation of each shaft 27 will give two reciprocations to the valve stems 30 of the valves 23 and 24. Of course, the cams 29 are set reversely to the cams 28, that is in quartering relation to these cams so that when the inlet valves 23 are opened, the outlet valve 24 will be closed, and vice versa. It will be understood, of course, that this is the gearing used where a single acting pump is to deliver a 75 charge of air for four cylinders, and I do not wish to be limited to the use of four valves as illustrated but these four valves are used simply for the purpose of securing ample inlet port area and ample outlet port 80 area. Obviously a greater or less number of valves may be used and these valves may be actuated in other ways, depending upon the character of the engine and other service factors. 85

Leading from each chamber 21 is a duct or pipe 31 which leads into a common chamber 32, which at the end 33 is connected to the carbureter D at the open end d, this end 33 forming an outlet port communicating with the carbureter and supplying air thereto. The casing 32 is also formed with a relief port 34, and disposed within the bottom of the chamber 32 and illustrated as rotatably mounted on the walls thereof is a relief valve 35 having a plurality of radially disposed ports 36 and provided with a valve operating arm 37. The valve is pivoted upon a pintle 38. This valve, as will be obvious from Figure 5, may be shifted to entirely 90 close the relief port 34 or may be shifted so as to be entirely open. When the valve is entirely closed, all of the air coming from the compressor and compressing pump 10 is forced through the carbureter and into that 95 engine cylinder which is on its suction stroke. If the relief port be entirely open, the engine will only secure air at atmospheric pressure, and it will be obvious that if this valve be in an intermediate position, part of the air forced into the duct 31 will pass into the carbureter and part of the air will be relieved and thus it will be obvious that by adjusting this valve 35, any desired 100 amount of air under pressure can be forced through the carbureter to compensate for the thinness of the air at any particular altitude and to secure through the engine a supply of air equal to that which it would normally require at sea level. 105

In the construction which I have illustrated, the cylinders 10 have a capacity twice that of any one of the cylinders F of the engine, and thus it will be seen that as the 5 pistons 11 operate at twice the speed of the pistons in the cylinders F, each pumping cylinder 10 will provide air under pressure for four cylinders, and thus the two cylinders illustrated will take care of an eight-cylinder motor of a V-type.

Attention is called to the fact that with my construction there is no back pressure due to using the exhaust as a means for driving an air compressing pump, and furthermore that the cylinders of the pump are disposed between the engine bank B and the propeller F, and that such a disposition of the pump makes it possible to apply this pump to aeroplane engines without in any 20 way changing the form of the engine and without disturbing in any way the balance of the engine or of the aeroplane.

One of the important features of my invention resides in the fact that with this device, while it is possible to compensate by its use for the gradual thinning of the air as the machine rises, yet there is no danger of pre-ignition. Superchargers known to me are only brought into use at a certain altitude 30 for the reason that if the pump were used to its full power below the altitude for which it was designed, it would cause pre-ignition, due to supercompression in the engine cylinders. With my construction, the pilot has 35 at all times a very delicate and exact control over the amount of supercharging air which is forced into the engine upon the suction stroke thereof. There are no clutches to operate or other variable compression mechanism, the mechanism is extremely simple and within standard practice, and the only controlling mechanism necessary is the controlling valve 35 and the means whereby it may be operated, which means is under control 40 of the pilot at all times and requires no delicate manipulation.

It will be seen that the portion 34 constitutes in effect a chamber connected at one end to a source of air under pressure and at the opposite end connected to the carburetor, and that the valve 35 and the relief port may be adjusted to an extent sufficient to permit the escape of excess air from the duct or chamber 31, and that the greater the opening 45 of the relief valve, the less the pressure above atmospheric pressure of air entering the carburetor, while when the relief port is entirely closed, the pressure of air passing through the carburetor will be the same as the pressure of the air as it is discharged from the compression pump.

While in Figures 1 to 5 I have illustrated twin single acting pumps connected to the two sets of cylinders of a V-type engine, in 55 Figures 6 to 9 I have illustrated a single

pumping cylinder operatively connected to two sets of engine cylinders and constituting a double acting pump. In these figures, B designates the engine block and A the crank case of the engine, D designating the carburetor, C the intake manifold branch leading from the carburetor on the middle line of the engine, and c the branches leading laterally from the branch C and connecting to the intake manifold c'. All of these parts may be of any usual or suitable construction.

Disposed between the engine bank B and the propeller F mounted on the crank shaft E is a double acting pump cylinder 39. This is shown as a fin cooled cylinder. 50 Within the cylinder is disposed a piston 40 connected by the connecting rod 41 to the crank 42 of a crank shaft 43 mounted in suitable bearings below the cylinder and driven by sprocket wheels 44 and 46 and 55 chain 45, the wheels 44 being mounted upon the crank shaft E and the wheel 46 being mounted upon the crank shaft 43, this gearing driving the crank shaft 43 at a speed twice that of the crank shaft E. The upper 60 end of the cylinder 39 is shown as provided with an inlet hood 47 having two inlet openings extending into the upper end of the cylinder 39 and controlled by two inlet valves 48, the stems 49 of which reciprocate within tubular guides 50.

There are two inlet valves 51 in the upper end of the cylinder whose stems extend outward through a discharge pipe 52, these stems being designated 53. The lower end of the cylinder is formed with a well 54 within which the crank 42 revolves, which well communicates with the lower end of the cylinder 39 and this well is provided, as illustrated in Figure 9, with two inlet ports 55 and two outlet ports 56. The inlet ports are controlled by valves 57 having stems extending out through suitable bushings and the outlet ports are controlled by valves 58 whose stems extend outward through suitable bushings, all as illustrated in Figure 9.

For the purpose of operating the inlet valves 48 and the outlet valves 51 in the upper end of the engine, I provide a rocker arm 59 (see Figure 8) which at its forward end is branched or T-shaped so as to engage both stems 49 of the valves 48. The rear end of this rocker arm is engaged by a vertically reciprocating rod 60, which rod extends downward vertically just behind the cylinder 39 and is supported in suitable guides and is engaged by a cam 61 mounted upon the crank shaft 43 of the pump. The stems 53 of the valves 51 are engaged by an approximately U-shaped rocker 62 pivoted at 63 and reciprocated by a longitudinally extending rod 64 which extends down between the cylinder 39 and the outlet pipe 52 and is engaged by a cam 65 mounted upon the crank rod 43. These cams 61 and 65

are, of course set reversely to each other so that the rods 60 and 61 will be alternately raised. When these rods are raised, they will obviously depress each its own pair of valves. Thus the inlet valves 48 will be opened alternately to the valves 51, the lower pair of inlet valves is operated by a transversely extending rock shaft 66 having a medially disposed, rearwardly extending arm 67 which engages with a contact rod 68 mounted in a suitable guide and reciprocated by means of a cam 69 on the crank shaft 43. The ends of the shaft 66 carry upon them the upwardly extending contact arms 70 which engage with the valve stems 71 of the valves 55. These valves are held closed by springs and are opened by the inward movement of the arms 70 due to the action of the cam 69. The outlet valves 58 are also held closed by springs and are operated by arms 72 mounted upon a transverse shaft 73 having a horizontally extending arm 74 which is engaged by a collar 75 mounted upon the reciprocating rod 60 so that the outlet valves 58 which control the outlet from the lower end of the cylinder are opened at the same time that the inlet valves at the upper end of the cylinder open, while the cam 69 is so timed that the inlet valves for the lower end of the cylinder open when the outlet valves 51 for the upper end of the cylinder open. Thus while the valves are opened for suction at one end of the cylinder, the outlet valves are opened for discharge at the other end of the cylinder, and vice versa.

A pipe or duct 76 extends from the chambers 54 on the outlet side of the seats 56, as illustrated in Figures 7 and 9, this branch pipe or duct 76 opening into the duct or pipe 52. It will thus be seen that a constant current of air under pressure is being discharged at all times into the carbureter unless the relief valve be fully opened to an extent where the pressure in excess of the atmospheric pressure is relieved. The relief valve is designated 35—36 and its operating

arm 37, as in Figures 1 to 5. This relief valve operates in exactly the same manner as heretofore described.

This construction is in principle the same as described in Figures 1 to 5 and only differs therefrom in that a single compression pump is used and in that this compression pump is illustrated as a double acting pump where the pumps heretofore described were single acting pumps. This form of mechanism tends to reduce weight by providing a single pumping cylinder instead of twin pumping cylinders, this single pumping cylinder pumping air for both sets of engines. It is, however, slightly more complicated as regards its valve gear.

I claim:—

The combination with an aeroplane engine of the V-type having two sets of cylinders disposed in divergent relation, a crank shaft, a propeller mounted upon the crank shaft, and a carbureter for both sets of cylinders, said carbureter having an inlet port, of two divergently related pumping cylinders disposed between the engine bank and the propeller and above the crank shaft and having a capacity approximately double that of any of said cylinders and having inlet ports and outlet ports, a housing disposed between the inner ends of the pumping cylinders and common to both of said pumping cylinders, a crank shaft disposed within the housing, pistons operating in the cylinders and operatively connected to the last named crank shaft, an operative driving connection between the first and last named crank shafts, valves controlling the inlet and outlet of air from said pumping cylinders, engine driven means for operating the said valves, and a tubular connection leading from the outlet of each pumping cylinder to the carbureter port and having a relief port, and manually controlled means for opening or partly opening the relief port.

In testimony whereof I hereunto affix my signature.

VINTON U. D. PIERCE.
